PAPER MAKING PULP REFINER

Joseph Baxter, Jr., Franklin, Ohio, assignor to The Black-Clawson Company, Hamilton, Ohio, a corporation of Ohio

Filed Feb. 14, 1961, Ser. No. 89,281

9 Claims. (Cl. 241—163)

This application relates generally to refining apparatus for use in the preparation of paper making stock, and more particularly to apparatus for effecting defibering of paper making pulp prior to the final refining thereof.

The invention is particularly concerned with the treatment of pulp which still contains lumps or bundles of fibers, such as defibered chips, pulp laps, waste papers and the like, and which therefore requires separation into individual fibers before it can properly be treated in a Jordan or similar refiner for developing desired fiber characteristics.

It is a primary object of the invention to provide rotary refining apparatus of novel construction for paper making pulp as outlined above which is capable of effecting complete defibering in a single pass of the pulp therethrough with minimum possibility that any lumps or bundles can slip through without being defibered.

It is particularly an object of the invention to provide refining apparatus having the above characteristics which is of such construction that multiple separate refining zones are established therein in stepped relation from the standpoint of refining action such that the entering lumps or bundles of fibers are progressively reduced in size by the different zones or stages of progressively more severe defibering action.

Another object of the invention is to provide refining apparatus as outlined above which is of outstanding simplicity and economy of construction, especially with respect to the refining elements which perform the defibering action therein.

An additional and more specific object of the invention is to provide refining apparatus for the purposes outlined above wherein there is a rotor and a stator or shell which carry a plurality of rows of substantially matching or complementary teeth, such as external and internal gear teeth respectively, arranged with relatively slight radial clearance to define a corresponding plurality of working zones, and which rows of teeth are progressively finer from the inlet to the outlet of the shell so that each pair of rows has a greater number of teeth therein than the preceding pair to provide correspondingly more intense defibering action on the stock passing therebetween.

It is a further object of the invention to provide refining apparatus as outlined in the preceding paragraph wherein each pair of rows of teeth not only has a greater number of teeth therein than the preceding pair of rows toward the inlet of the shell, but also each pair of rows is of greater diameter than the preceding pair to produce a correspondingly increased peripheral speed of the rotor teeth in each refining zone from the inlet of the shell to its outlet.

Additional objects and advantages of the invention will be apparent from the following description, the accompanying drawings and the appended claims.

In the drawings—

FIG. 1 is a side elevational view of refining apparatus constructed in accordance with the invention;

FIG. 2 is an end elevation looking from right to left in FIG. 1;

FIG. 3 is an enlarged fragmentary section on the line 3—3 of FIG. 2;

FIG. 4 is an enlarged fragment of FIG. 3 showing the several refining zones in the apparatus of FIGS. 1—3;

FIG. 5 is an enlarged fragmentary section on the line

5—5 of FIG. 4 showing the teeth in the first and least severe refining zone;

FIG. 6 is a section similar to FIG. 5 on the line 6—6 of FIG. 4 showing the teeth in the first intermediate refining zone;

FIG. 7 is a section similar to FIG. 5 on the line 7—7 of FIG. 4 showing the teeth in the second intermediate refining zone; and

FIG. 8 is a view similar to FIG. 5 on the line 8—8 of FIG. 4 showing the teeth in the last and most severe refining zone.

Referring to the drawings, which illustrate a preferred embodiment of the invention, the main body of the refiner comprises a lower body section 10 and an upper body section 11 which define a generally cylindrical chamber open at one end thereof, and this open end is substantially closed by an annular packing box 12 through which a drive shaft 13 projects into the interior of the refiner body. The shaft 13 is supported exteriorly of the refiner body by suitable bearings within bearing housings 15 and 16 and a housing spacer 17, all of which are in turn supported on a bearing support frame 20 bolted or otherwise secured to the body section 10 and packing box 12.

25 A tangentially arranged inlet port 22 leads into the inlet chamber 23 within the refiner body 10—11, and a tangentially arranged outlet port 24 leads from the outlet chamber 25 at the opposite side of the refiner body from the inlet port 22. There is a similar tangentially arranged port 26 opposite the inlet port 22 which forms a trap for tramp metal and is provided with a suitable clean-out door assembly indicated generally at 27. Access to the inlet chamber 23 is also available through a port 28 in the upper body section 11 which is normally closed by a flange 29 as shown.

The inlet chamber 23 and outlet chamber 25 within the refiner body are separated by the relatively rotating rotor and stator which define the stepped refining zones in which pulp is defibered as it passes from the inlet chamber 23 to the outlet chamber 25. The stator or shell is indicated generally at 30 and is a separately formed part which is removably supported within an annular flanged boss formed by complementary parts 31 and 32 of the body sections 10 and 11 respectively. The shell 30 is secured against rotation by a key 33 and cooperating keyway 34 as shown in FIG. 3, and it is held axially in position by a half ring 35 which is secured to the boss section 32 by a screw 36 and by similar screws 37 to the shell 30 itself.

The rotor assembly is indicated generally at 40 and includes a hub 41 which is preferably keyed on the tapered end of the shaft 13 and is held axially in position by the cap 42 bolted to the end of the shaft 13. The rotor hub 41 carries the rotor 44 which is an annular body secured on the hub 41 as shown by means of the clamp ring 45 and bolts 46.

The shell 30 and rotor 40 are each provided with a plurality of circumferential rows of respectively inner and outer teeth of different sizes, spacing and radius which thus define a series of stepped refining zones of progressively more severe action on the pulp as the stock passes from the inlet chamber 23 to the outlet chamber 25. In the unit shown in FIGS. 3 and 4, there are four of these stepped refining zones identified as A—D respectively in FIG. 4, and the teeth which define the individual zones are shown in enlarged detail in FIGS. 5—8 as now described.

FIG. 5 shows the first refining zone A entered by the stock from the inlet chamber 23, and in accordance with the invention the refining action in this zone is relatively gentle. The portion of the rotor 40 in this zone is provided with a plurality of relatively coarse teeth 50 each of which has a radially outer surface 51 of substantial

area, these surfaces 51 being cylindrically curved about the center of the rotor 40. The teeth 50 are separated by grooves 52 roughly complementary in individual radial section to the teeth themselves so that each groove has a generally flat bottom surface 53.

The shell 30 is provided with a row of internal teeth 55 in the zone A which are approximately complementary in section to the teeth 50 in that the dimensions of their radially inner surfaces 56 are approximately equal to the corresponding dimensions of the rotor teeth surfaces 51. There are the same number of shell teeth 55 as there are rotor teeth 50 so that there are similar grooves 57 therebetween, each of these grooves having a substantially flat bottom 58. By way of illustrative example, in one satisfactory embodiment of the invention, there are forty-eight teeth 50 having an outer radius of approximately 7 inches and also forty-eight teeth 55, and their respective dimensions are such that when the rotor and shell are assembled, there is a radial spacing of the order of .150 inch between the teeth surfaces 51 and 56.

FIG. 6 illustrates the teeth which form the refining zone B next to the zone A, and these teeth are proportioned to provide a somewhat more severe refining action. The rotor teeth 60 are similar to the teeth 50, and they have similar radially outer surfaces 61 and are separated by grooves 62 having flat bottoms 63. The teeth 60, however, are of individually smaller radial dimensions and are formed on a somewhat greater radius than the teeth 50. Preferably this radius difference is such that the groove bottoms 63 are spaced radially beyond the tooth surfaces 51, and satisfactory results have been obtained with this radius difference being of the order of .365 inch. These differences in proportions and radius also make it possible to provide a substantially greater number of teeth 60 than teeth 50, and satisfactory results have been obtained with a rotor having sixty-four teeth 60 as compared with forty-eight teeth 50. Also, it will be noted that the stator teeth 55 extend radially inwardly beyond the groove bottoms 63 in overlapping relation with the rotor teeth 60 which similarly overlap the shell grooves 57.

The complementary shell teeth 65 in FIG. 6 differ from the shell teeth 55 in the same manner that the rotor teeth 50 differ from the rotor teeth 60. Accordingly, there are the same number of shell teeth 65 as there are rotor teeth 60, and the radial inner surfaces 66 of the teeth 65 substantially match the dimensions of the rotor teeth surfaces 61. Preferably the radial spacing between the tooth surfaces 61 and 66 should be less than that between the surfaces 51 and 56, and satisfactory results have been obtained with a spacing of the order of .063 inch. It will be seen that the greater number of teeth 60 and 65 together with their greater radii than the teeth 50 and 55 will cause a substantially greater tooth speed as well as in the number of passes of tooth surfaces 61 with respect to each tooth surface 66. This result together with the closer spacing of the teeth 60 and 65 will produce a substantially more severe refining action on the pulp than in the zone A defined by the teeth 50-55.

FIG. 7 illustrates the teeth which form the next intermediate refining zone C downstream from the zone B. As shown, the rotor teeth 70 are substantially smaller than the rotor teeth 60, and each tooth 70 has a radially outer surface 71 of substantial dimensions which, however, are somewhat less than the dimensions of the surfaces 51 and 61. Also the teeth 70 are formed on a greater radius than the teeth 60, for example a radius for the groove bottoms 73 which is approximately .220 inch greater than that of the tooth surfaces 61, and also a radius for the surfaces 71 which is at least .030 inch greater than that of the shell groove bottoms 68. With sixty-four teeth 60 and the other dimensions as previously stated, satisfactory results have been obtained with eighty teeth 70.

The complementary shell teeth 75 in FIG. 7 are equal

in number to the rotor teeth 70, and the dimensions of their radially inner surfaces 76 substantially match those of the tooth surfaces 71. Satisfactory results have been obtained when in the assembled relation of the rotor and shell, the spacing between the surfaces 71 and 76 is of the order of .060 inch.

FIG. 8 illustrates the teeth which form the last refining zone D wherein the most severe defibering action occurs. The teeth 80 are similar to the other rotor teeth, having similar outer surfaces 81, but these teeth 80 are the smallest on the rotor and are set on the largest radius, for example a radius approximately .360 inch greater than that of the tooth surfaces 71 and with the groove bottoms 83 approximately .125 inch greater in radius than the tooth surfaces 71. This makes it possible to have a still greater number of teeth 80 than teeth 70, and satisfactory results have been obtained with ninety-six teeth 80 when the numbers and dimensions of the other teeth are as previously noted.

20 The complementary shell teeth 85 are equal in number to the rotor teeth 80 and have a radially inner surface 86 substantially matching the rotor teeth surfaces 81. In the assembled relation of the rotor and stator, satisfactory results have been obtained with these teeth surfaces of the order of .063 inch apart. It will also be seen that the progressive reduction in dimensions of each set of teeth correspondingly reduces the radial depth of the grooves therebetween, for example from a maximum of .524 inch and .536 inch for the grooves 52 and 57 to a minimum of .234 inch and .266 inch for the grooves 82 and 87 respectively.

25 In operation with the apparatus constructed as disclosed, the stock comprising the pulp to be defibered enters the inlet chamber 23 tangentially to produce an initial circulatory motion therein, and it is discharged through the outlet port 25 after passing through the successive refining zones defined by the teeth of the rotor and shell. As noted, the teeth in each successive zone are progressively smaller and more closely spaced to produce a correspondingly progressively more severe refining 30 action in each zone. Thus, with twice as many teeth in the final zone D as in the initial zone A, the chips or particles of fiber are broken down into smaller sizes as they pass through successive zones until they are substantially 35 completely defibered before they leave the final zone D.

40 One of the major advantages of the operation of the apparatus of the invention derives from the fact that its construction effectively inhibits the possibility of large chips or particles slipping through without effective defibering. For example, if defibering is done according to conventional practice by means of a conventional Jordan, it is possible for some large particles to be channeled completely through the Jordan by way of the grooves between the plug and shell bars and thus never be subjected to 45 mechanical action. In the apparatus of the invention, such result is prevented by a number of factors. One is that the grooves between the teeth in each successive zone are progressively smaller. Another is the arrangement of adjacent rows of teeth with each row of shell teeth 50 radially overhanging the entrances to the grooves between the adjacent rotor tooth on the downstream side so that these grooves in the lower teeth are successively swept across the end faces of the shell teeth and there is never a through channel available to large particles. Still another factor contributing to this result as well as generally effective defibering is that there is an abrupt change in circumferential speed from zone to zone, due to the progressively greater diameters of the rotor across each successive row of rotor teeth.

55 The apparatus of the invention also offers substantial advantages from the standpoint of ease of manufacture and maintenance. Thus the parts of the rotor and shell which include the teeth are readily produced by conventional casting and machining techniques, and it has also 60 been found practicable in the practice of the invention

to employ rotor and shell assemblies of different sizes in the same body, depending upon the capacity desired in the finished unit. Maintenance is extremely simple, particularly the exchange of the rotor and shell when replacement is required. It is merely necessary to remove the upper body section 11, which may conveniently be done by means of the eye-bolt 90, and the shell 30 can be similarly removed by simply releasing the screws 37 and then sliding the shell into the inlet chamber 23 free of the rotor. The rotor assembly 40 can then be similarly removed after releasing the bolts 46, and replacement of the new rotor and shell will follow the reverse steps. Note that with the construction of the body as shown, no extra space is needed beyond either end of the apparatus in which to carry out replacement operations as is the case with a Jordan.

A further practical advantage of the apparatus of the invention lies in the fact that the parts are automatically assembled into proper working relation and are not subject to adjustment. It is therefore assured that the apparatus will at all times operate in the manner for which it was designed and that its intended operating conditions cannot be altered by unauthorized adjustment such as can occur in the case of a Jordan or other refiner wherein the spacing of the relatively moving working parts can be adjusted during operation. It will be seen that this advantage is related to the ease of replacement of worn working parts as already discussed, since it is then more desirable to install a new rotor and shell than to attempt to renovate worn parts by adjustment or the like.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. Refining apparatus of the character described for liquid slurry stock, comprising a shell defining a refining chamber, means in said shell forming an inlet chamber and an outlet chamber on opposite sides of said refining chamber, a rotor mounted for rotation in said shell and including a rotor body extending through said refining chamber, said rotor body having thereon at least two circumferential rows of substantially uniform and uniformly spaced teeth forming working surfaces, said teeth in said row nearest said inlet chamber being of substantially greater depth and spacing than said teeth in said row nearest said outlet chamber to provide a correspondingly greater number of teeth in said row nearest said outlet chamber, said shell having thereon rows of teeth substantially complementary to and in radially spaced and overlying relation with said teeth on said rotor body to define therewith a correspondingly plurality of stepped working zones for the stock passing from said inlet chamber to said outlet chamber, and said teeth and the grooves therebetween in each of said rows extending substantially parallel with the axis of rotation of said rotor to minimize the pumping action of said apparatus and to effect a substantially uniform rate of axial travel of the stock with respect to each of said zones.

2. Refining apparatus of the character described for liquid slurry stock, comprising a shell defining a refining chamber, means in said shell forming an inlet chamber and an outlet chamber on opposite sides of said refining chamber, a rotor mounted for rotation in said shell and including a rotor body extending through said refining chamber, said rotor body having thereon at least two circumferential rows of substantially uniform and uniformly spaced teeth forming working surfaces, said rotor being of lesser diameter across the first said row of teeth adjacent said inlet chamber than across the last said row nearest said outlet chamber, said teeth in said first row being of substantially greater depth and spacing than said teeth in said last row to provide a correspondingly

greater number of teeth in said last row, said shell having therein rows of teeth substantially complementary to and in radially spaced and overlying relation with said teeth on said rotor body to define therewith a corresponding plurality of stepped working zones for the stock passing from said inlet chamber to said outlet chamber, and said teeth and the grooves therebetween in each of said rows extending substantially parallel with the axis of rotation of said rotor to minimize the pumping action of said apparatus and to effect a substantially uniform rate of axial travel of the stock with respect to each of said zones.

3. Refining apparatus of the character described for liquid slurry stock, comprising a shell defining a refining chamber, means in said shell forming an inlet chamber and an outlet chamber on opposite sides of said refining chamber, a rotor mounted for rotation in said shell and including a rotor body extending through said refining chamber, said rotor body having thereon at least two circumferential rows of substantially uniform and uniformly spaced teeth forming working surfaces, said teeth in the first said row nearest said inlet chamber being of substantially greater depth and spacing than said teeth in the last said row nearest said outlet chamber to provide a correspondingly greater number of teeth in said last row, said shell having therein rows of teeth substantially complementary to and in radially spaced and overlying relation with said teeth on said rotor body to define therewith a corresponding plurality of stepped working zones for the stock passing from said inlet chamber to said outlet chamber, said teeth and the grooves therebetween in each of said rows extending substantially parallel with the axis of rotation of said rotor to minimize the pumping action of said apparatus and to effect a substantially uniform rate of axial travel of the stock with respect to each of said zones, and said teeth in at least one of said sets of complementary rows being of different axial length from said teeth in another of said sets of complementary rows to provide correspondingly different dwell times for the stock in the respective said working zones.

4. Refining apparatus of the character described for liquid slurry stock, comprising a shell defining a refining chamber, means in said shell forming an inlet chamber and an outlet chamber on opposite sides of said refining chamber, a rotor mounted for rotation in said shell and including a rotor body extending through said refining chamber, said rotor body having thereon at least three adjacent circumferential rows of substantially uniform and uniformly spaced teeth forming working surfaces, said teeth in the first said row nearest said inlet chamber being of maximum depth and spacing with respect to each of the other said rows, said teeth in each other said row being of progressively lesser depth and spacing with respect to said teeth in said first row to provide a correspondingly greater number of teeth in each of said rows progressively from said inlet chamber to said outlet chamber, said shell having therein rows of teeth substantially complementary to and in radially spaced and overlying relation with said teeth on said rotor body to define therewith a corresponding series of stepped working zones for the stock passing from said inlet chamber to said outlet chamber, and said teeth and the grooves therebetween in each of said rows extending substantially parallel with the axis of rotation of said rotor to minimize the pumping action of said apparatus and to effect a substantially uniform rate of axial travel of the stock with respect to each of said zones.

5. Refining apparatus of the character described for liquid slurry stock, comprising a shell defining a refining chamber, means in said shell forming an inlet chamber and an outlet chamber on opposite sides of said refining chamber, a rotor mounted for rotation in said shell and including a rotor body extending through said refining chamber, said rotor body having thereon at least three adjacent circumferential rows of substantially uniform and

uniformly spaced teeth forming working surfaces, the diameter of said rotor body across successive said rows of teeth being progressively greater from said inlet chamber to said outlet chamber, said teeth in the first said row nearest said inlet chamber being of maximum depth and spacing with respect to each of the other said rows, said teeth in each other said row being of progressively lesser depth and spacing with respect to said teeth in said first row to provide a correspondingly greater number of teeth in each of said rows progressively from said inlet chamber to said outlet chamber, said shell having therein rows of teeth substantially complementary to and in radially spaced and overlying relation with said teeth on said rotor body to define therewith a corresponding series of stepped working zones for the stock passing from said inlet chamber to said outlet chamber, and said teeth and the grooves therebetween in each of said rows extending substantially parallel with the axis of rotation of said rotor to minimize the pumping action of said apparatus and to effect a substantially uniform rate of axial travel of the stock with respect to each of said zones.

6. Refining apparatus of the character described for liquid slurry stock, comprising a shell defining a refining chamber, means in said shell forming an inlet chamber and an outlet chamber on opposite sides of said refining chamber, a rotor mounted for rotation in said shell and including a rotor body extending through said refining chamber, said rotor body having thereon at least three adjacent circumferential rows of substantially uniform and uniformly spaced teeth forming working surfaces, the diameter of said rotor body across successive said rows of teeth being progressively greater from said inlet chamber to said outlet chamber, said teeth in the first said row nearest said inlet chamber being of maximum depth and spacing with respect to each of the other said rows, said teeth in each other said row being of progressively lesser depth and spacing with respect to said teeth in said first row to provide a correspondingly greater number of teeth in each of said rows progressively from said inlet chamber to said outlet chamber, and said shell having therein rows of teeth substantially complementary to and in radially spaced and overlying relation with said teeth on said rotor body to define therewith a corresponding series of stepped working zones for the stock passing from said inlet chamber to said outlet chamber, said teeth and the grooves therebetween in each of said rows extending substantially parallel with the axis of rotation of said rotor to minimize the pumping action of said apparatus and to effect a substantially uniform rate of axial travel of the stock with respect to each of said zones, and said teeth in each said row in said shell extending radially inwardly in completely overlapping relation with said teeth in the adjacent row downstream therefrom on said rotor and with the spaces between adjacent said rotor teeth.

7. Refining apparatus of the character described for liquid slurry stock, comprising a shell defining a refining chamber, means in said shell forming an inlet chamber and an outlet chamber on opposite sides of said refining chamber, a rotor mounted for rotation in said shell and including a rotor body extending through said refining chamber, said rotor body having thereon at least two circumferential rows of substantially uniform and uniformly spaced teeth, each of said teeth having a radially outer surface of a substantial circumferential dimension defining a working surface of correspondingly substantial area, adjacent teeth in each said row being separated from each other by a groove which is roughly complementary in radial section to each of the teeth in said row, said teeth in said row nearest said inlet chamber being of substantially greater depth and spacing than said teeth in said row nearest said outlet chamber, said shell having therein rows of teeth substantially complementary to and in radially spaced and overlying relation with said teeth on said rotor

body to define therewith a corresponding plurality of stepped working zones for the stock passing from said inlet chamber to said outlet chamber, and each of said shell teeth having a radially inner surface approximately equal in the circumferential dimension thereof to each of the adjacent rotor teeth to provide working surfaces on said shell teeth of substantially the same areas as said working surfaces on said rotor teeth, adjacent teeth in each said row of shell teeth being separated from each other by a groove which is roughly complementary in radial section to said adjacent shell teeth, each of said teeth and each of said grooves extending substantially parallel with the axis of rotation of said rotor and being of substantially uniform radial dimensions to effect a substantially uniform rate of travel of the stock along each of said grooves.

8. Refining apparatus of the character described for liquid slurry stock, comprising a shell defining a refining chamber, means in said shell forming an inlet chamber and an outlet chamber on opposite sides of said refining chamber, a rotor mounted for rotation in said shell and including a rotor body extending through said refining chamber, said rotor body having thereon at least two circumferential rows of substantially uniform and uniformly spaced teeth, each of said teeth having a radially outer surface of a substantial circumferential dimension defining a working surface of correspondingly substantial area, adjacent teeth in each said row being separated from each other by a groove which is roughly complementary in radial section to each of the teeth in said row, said rotor being of lesser diameter across the first said row of teeth adjacent said inlet chamber than across the last said row nearest said outlet chamber, said teeth in said first row being of substantially greater depth and spacing than said teeth in said last row to provide a correspondingly greater number of teeth in said last row, said shell having therein rows of teeth substantially complementary to and in radially spaced and overlying relation with said teeth on said rotor body to define therewith a corresponding plurality of stepped working zones for the stock passing from said inlet chamber to said outlet chamber, and each of said shell teeth having a radially inner surface approximately equal in the circumferential dimension thereof to each of the adjacent rotor teeth to provide working surfaces on said shell teeth of substantially the same areas as said working surfaces on said rotor teeth, adjacent teeth in each said row of shell teeth being separated from each other by a groove which is roughly complementary in radial section to said adjacent shell teeth, each of said teeth and each of said grooves extending substantially parallel with the axis of rotation of said rotor and being of substantially uniform radial dimensions to effect a substantially uniform rate of travel of the stock along each of said grooves.

9. Refining apparatus of the character described for liquid slurry stock, comprising a shell defining a refining chamber, means in said shell forming an inlet chamber and an outlet chamber on opposite sides of said refining chamber, a rotor mounted for rotation in said shell and including a rotor body extending through said refining chamber, said rotor body having thereon at least three adjacent circumferential rows of substantially uniform and uniformly spaced teeth, each of said teeth having a radially outer surface of a substantial circumferential dimension defining a working surface of correspondingly substantial area, adjacent teeth in each said row being separated from each other by a groove which is roughly complementary in radial section to each of the teeth in said row, the diameter of said rotor body across successive said rows of teeth being progressively greater from said inlet chamber to said outlet chamber, said teeth in the first said row nearest said inlet chamber being of maximum depth and spacing with respect to each of the other said rows, said teeth in each other said row being of progressively lesser depth and spacing with respect to

said teeth in said first row to provide a correspondingly greater number of teeth in each of said rows progressively from said inlet chamber to said outlet chamber, said shell having therein rows of teeth substantially complementary to and in radially spaced and overlying relation with said teeth on said rotor body to define therewith a corresponding series of stepped working zones for the stock passing from said inlet chamber to said outlet chamber, and each of said shell teeth having a radially inner surface approximately equal in the circumferential dimension thereof to each of the adjacent rotor teeth to provide working surfaces on said shell teeth of substantially the same areas as said working surfaces on said rotor teeth, adjacent teeth in each said row of shell teeth being separated from each other by a groove which is roughly complementary in radial section to said adjacent shell teeth, each of said teeth and each of said grooves extending substan-

tially parallel with the axis of rotation of said rotor and being of substantially uniform radial dimensions to effect a substantially uniform rate of travel of the stock along each of said grooves.
